C. A. BODDIE,
FURNACE REGULATOR SYSTEM,
FILED AUG. 26, 1919.

UNITED STATES PATENT OFFICE.

CLARENCE A. BODDIE, OF PITTSBURGH, PENNSYLVANIA, ASSIGNOR TO WESTINGHOUSE ELECTRIC & MANUFACTURING COMPANY, A CORPORATION OF PENNSYLVANIA.

FURNACE-REGULATOR SYSTEM.

Application filed August 26, 1919. Serial No. 319,903.

To all whom it may concern:

Be it known that I, CLARENCE A. BODDIE, a citizen of the United States, and a resident of Pittsburgh, in the county of Allegheny 5 and State of Pennsylvania, have invented a new and useful Improvement in Furnace-Regulator Systems, of which the following is a specification.

My invention relates to regulator systems 10 and particularly to regulator systems for governing the operation of the movable electrodes in electric furnaces.

One object of my invention is to provide a furnace-regulator system that shall be governed in accordance with the current and 15 the voltage conditions of the furnace and that shall be substantially free from so-called hunting action.

Heretofore, it has been customary to control each movable electrode of an electric furnace by a main magnet which was energized in accordance with the current flowing through it and to vary the energization of the winding of said magnet to prevent 20 hunting action. The above operation of a furnace electrode is fairly satisfactory under normal operating conditions, but, at times, trouble is encountered if no account is taken of the voltage across the electrode arc. Thus, 25 in a three-phase electric furnace, the resistance of the material being treated may vary in different parts of the furnace and, consequently, the various electrode circuits may have different resistance values. In such 30 case, the current flowing through the various electrodes will be varied in a manner to produce different arcs by the different electrodes and, consequently, to produce different heating effects in the furnace. It has 35 been proposed to control the main magnet of the furnace-regulating system not only in accordance with the current flowing through the electrode but also in accordance with the potential across the electrode arc. 40 However, in such regulating systems, it is 45 customary to shunt the current winding by means of an adjusting resistor for governing the energization of the current winding but such adjusting resistor causes a considerable lag in the current flowing through the

current winding and, consequently, the currents flowing through the current winding and the potential winding will not co-act to jointly control the operation of the electrode.

55

In a furnace-regulator system constructed in accordance with my invention, each movable electrode is provided with a motor which is controlled by a main magnet not only in accordance with the current flowing through the electrode but also in accordance with the voltage obtaining across the electrode arc. The main magnet comprises a winding which is energized in accordance with the current flowing through the electrode and a 60 second winding which is energized in accordance with the potential obtaining across the electrode arc. The current winding is shunted by means of an adjusting resistor which produces a very low power factor in 65 the current winding and, consequently, some means must be provided for adjusting the currents flowing through the potential and the current windings to the same phase relation. In order to accomplish such object, an inductor is connected in series with the resistor which shunts the current winding for increasing the power factor of that winding and a second inductor is connected in circuit with the potential winding for 70 lowering the power factor of such winding.

75

The single figure of the accompanying drawing is a diagrammatic view of a furnace-regulator system embodying my invention.

85

Referring to the drawing, an electric furnace 1, comprising a receptacle 2 containing a bath of material 3 and three movable electrodes 4, 5 and 6, is directly connected to a three-phase supply circuit comprising conductors 7, 8 and 9.

90

Each of the electrodes 4, 5 and 6 is provided with an electrode motor and a regulator for adjusting the electrode in accordance with the voltage and the current conditions of the electrode circuit and, inasmuch as the associated motors and regulators are similar in construction and operation, it is deemed sufficient to illustrate and describe the construction and operation of but one 95 100

electrode motor and one regulator, namely, the motor and regulator which are associated with the electrode 6.

A motor 10, comprising an armature 11 and a field winding 12, is provided for raising and lowering the electrode 6 and is mechanically connected to the electrode in any suitable manner, as by means of a winding reel 13 and a flexible connector 14 which passes over a pulley 15. The field winding 12 is directly connected to an auxiliary supply circuit comprising conductors 16 and 17.

A main magnet 18, which is operated in accordance with the current and the voltage conditions of the circuit of the electrode 6, is provided for selectively operating two switches 19 and 20 and for connecting the armature 11 across the supply conductors 16 and 17 to rotate the motor 10 in a clockwise and in a counter-clockwise direction. The main magnet 18 comprises a current winding 21 which is connected to the three-phase supply conductor 9 by means of a current transformer 22 and a potential winding 23 which is connected across the arc produced by the electrode 6. The two windings 21 and 23 operate a core armature 24 which is provided with a dash-pot 25 for adjusting its operation and is pivotally connected to a contact arm 26. The contact arm 26 is fulcrumed at 27 and is provided with a main contact member 28 which engages contact members 29 and 30 according to the operative position of the main magnet 18.

The switch 19 comprises a winding 31, which is connected across the supply conductors 16 and 17 upon engagement between the contact members 28 and 30, and a core armature 32 which operates two switch members 33 and 34 and two interlock switch members 35 and 36. The two switch members 33 and 34 serve to connect the armature 11 across the supply conductors 16 and 17 for operating the motor 10 in a counter-clockwise direction to raise the electrode 6 and, consequently, to decrease the current flowing through said electrode. The interlock switch member 36 serves, upon operation of the switch 19, to complete a short-circuit across that portion of the current winding 21 which is included between taps 37 and 38 for preventing any hunting action.

The switch 20 comprises a winding 39, which is connected across the supply conductors 16 and 17 upon engagement between the contact members 28 and 29, and a core armature 40 which operates two switches 41 and 42 and two interlocking-switch members 43 and 44. The switch members 41 and 42 connect the armature 11 across the supply conductors 16 and 17 for rotating the motor 10 in a clockwise direction to lower the electrode 6 and, consequently, to increase the current flow through it. The interlock switch member 44, upon operation of the

switch 20, serves to open a short-circuit which normally obtains across that portion of the winding 21 which is included between taps 37 and 45 for preventing any hunting action when the electrode 6 is being lowered in the furnace. The interlock switch members 35 and 43, upon release of the two switches 19 and 20, complete an energizing circuit for a brake relay 46 from the supply conductors 16 and 17. The relay 46, upon operation, completes a dynamic-braking circuit through a resistor 47 for the armature 11 of the motor 10.

In order to adjust the current flow through the current winding 21 of the main magnet 18, it is necessary to shunt the winding by means of an adjustable resistor 50 and, inasmuch as such connection increases the lag of the current flowing through the winding 21, it is necessary to either decrease the lag of the current flowing through the winding 21 or to increase the lag of the current flowing through the winding 23 in order to obtain joint action on the core armature 24 by the two windings. Accordingly, a resistor 51 is connected in series with the winding 21, and an inductor 52 is connected in series with the resistor 50 for decreasing the lag of the current flowing through the winding 21 and, moreover, a resistor 53 and an inductor 54 are connected in series with the winding 23 in order to increase the lag of the current flowing through the winding 23. Accordingly, the lag in the current flowing through the winding 21 is reduced and the lag of the current flowing through the winding 23 is increased to bring the currents flowing through the two coils to the same phase relation.

In case a current above normal value flows through the electrode 6 or the potential across the arc produced by the electrode 6 is below normal value, the main magnet 18 is operated to effect engagement between the contact members 28 and 30. Thereupon, a circuit is completed from the supply conductors 16 and 17 for operating the switch 19. The motor 10 is rotated in a counter-clockwise direction for raising the electrode 6 to decrease the current flowing through it and to raise the potential across the arc produced by it.

If no anti-hunting means were provided in the system, the electrode 6 would be raised by the motor 10 until the main magnet 18 was operated by the obtaining of normal electric-circuit conditions. Consequently, the various moving parts of the regulator system and of the motor 10 would overtravel to raise the electrode 6 above the desired point and, consequently, to reduce the current flow through it below normal value. In order to prevent such overtravel and the consequent hunting action, the interlock switch member 36 short-circuited the winding 21.

cuits that portion of the winding 23 which is included between the taps 37 and 38 in order to change the setting of the main magnet 18 and effect separation of the contact members 28 and 30 just prior to the obtaining of normal electrode-circuit conditions.

In case the current flow through the electrode 6 is below normal value and the potential across the electrode 6 is above normal value, the main magnet 18 is operated to effect engagement between the contact members 28 and 29 for operating the switch 20. Upon operation of the switch 20, the motor 10 is rotated in a clock-wise direction for lowering the electrode 6 to increase the current flow through it and to decrease the potential across the electrode arc. Simultaneously with the operation of the motor 10, the interlock switch member 44 opens the short-circuit which normally obtains across that portion of the winding 21 which is included between the taps 37 and 45 for changing the setting of the main magnet 18. Thus, the magnet 18 is operated to effect separation of the contact members 28 and 29 just prior to the obtaining of normal electrode-circuit conditions for preventing any hunting action.

In the system above described, it will be noted that a main magnet is provided with a current and a potential winding for governing the operation of the associated electrode, not only in accordance with the current conditions of the furnace but also in accordance with the potential obtaining across the electrode arc. Moreover, means is provided for preventing any hunting action on the part of the regulator and for maintaining the currents in the potential and the current winding of the main magnet in the same phase relation.

Modifications in the system and arrangement and location of parts may be made within the spirit and scope of my invention, and such modifications are intended to be covered by the appended claims.

I claim as my invention:

1. In a furnace-regulator system, the combination with a movable electrode, and a motor for raising and lowering said electrode, of means comprising an electro-magnet for controlling said motor to maintain the electrode arc constant, said electro-magnet having a winding energized in accordance with the current flowing through the electrode and a winding energized in accordance with the potential across the electrode arc, and means for maintaining the currents flowing through said windings in the same phase relation.

2. In a furnace-regulator system, the combination with a movable electrode, and means comprising an electro-magnet having a current and a potential winding for

governing said electrode to maintain a constant electrode arc, of means for maintaining the currents in said windings in the same phase relation.

3. In a furnace-regulator system, the combination comprising a movable electrode, a magnet having a winding connected in series with the electrode and a second winding connected across the electrode arc, and resistors and inductors connected in various relations to said windings for adjusting the energization of the magnet and for regulating the phase relation of the currents in the windings.

4. In a furnace-regulator system, the combination comprising a movable electrode, means comprising a magnet having a current and a potential winding for maintaining a constant electrode arc, and means for varying the number of active turns of one of said windings to prevent any hunting action.

5. In a furnace-regulator system, the combination with a movable electrode, and a motor for raising and lowering said electrode, of a magnet having a winding energized in accordance with the current flowing through the electrode and a winding energized in accordance with the potential obtaining across the electrode arc for controlling said motor to maintain a constant electrode arc, and means comprising resistors and inductors for varying the impedance of the circuits of said windings to maintain the currents flowing through the windings in the same phase relation.

6. In a furnace-regulator system, the combination comprising a movable electrode, an electromagnet having a current and a potential winding, means controlled by said magnet for operating said electrode to maintain a constant electrode arc, and an inductor connected across one of said windings and a second inductor connected in series with the second winding for maintaining the currents in the two windings in the same phase relation.

7. In a furnace-regulator system, the combination with a movable electrode, and means comprising a magnet having a current and a potential winding for maintaining a constant electrode arc, of means for varying the number of active turns of one of said windings to prevent hunting action, and means inserted in the circuits of said windings for regulating the phase relation of the currents flowing through the windings.

8. In a regulator system, the combination with a movable electrode and a motor for raising and lowering said electrode, of a regulator for governing the operation of said motor to maintain a constant electrode arc, said regulator comprising an electro-magnet having a winding energized in accordance with the current flowing through

the electrode and a winding energized in accordance with the potential obtaining across the electrode arc, and means for varying the energization of said current winding to prevent hunting action.

9. In a furnace-regulator system, the combination comprising a movable electrode, means for raising and lowering said electrode, a regulator for governing the operation of said means to maintain a constant electrode arc, said regulator comprising an electromagnet having a current and a potential winding energized from the electrode circuit and means for varying the energization of the current winding to prevent hunting action.

10. In a furnace-regulator system, the combination comprising a movable electrode, means comprising a regulator for governing the operation of said electrode to maintain a constant electrode arc, said regulator comprising one electromagnet having a current and a potential winding energized from the

electrode circuit, and means for varying the energization of one of said windings to prevent hunting action. 25

11. In a furnace-regulator system, the combination with a movable electrode and a plural-coil electromagnet energized in accordance with electrode circuit conditions to maintain a constant electrode arc, of means for maintaining predetermined phase relations of the currents traversing said coils. 30

12. In a furnace-regulator system, the combination comprising a movable electrode, means comprising a plural-coil electromagnet energized in accordance with electrode circuit conditions to maintain a constant electrode arc and means for varying the effect of one of said coils to prevent hunting 35 action. 40

In testimony whereof, I have hereunto subscribed my name this 12th day of Aug., 1919.

CLARENCE A. BODDIE.
